Primary Examiner — Marissa J Cash(74) *Attorney, Agent, or Firm* — Timmer Law Group, PLLC(57) **CLAIM**

The ornamental design for an aircraft payload enclosure, substantially as shown and described.

DESCRIPTION

FIG. 1 is a front perspective view of an aircraft payload enclosure shown with the environmental rotor nacelles facing forward;

FIG. 2 is a front elevational view of the aircraft payload enclosure in FIG. 1;

FIG. 3 is a rear elevational view thereof;

FIG. 4 is a right side view thereof;

FIG. 5 is a left side view thereof;

FIG. 6 is a top view thereof; and,

FIG. 7 is a bottom view thereof.

The broken lines illustrate environmental subject matter only and form no part of the claimed design.
